V. Arthur & Isaac Co.

UNITED STATES PATENT OFFICE.

EDWARD E. GOLD, OF NEW YORK, N. Y.

CAR-HEATER.

No. 795,908.

Specification of Letters Patent.

Patented Aug. 1, 1905.

Application filed March 10, 1904. Serial No. 197,504.

To all whom it may concern:

Be it known that I, EDWARD E. GOLD, a citizen of the United States, residing in the borough of Manhattan, city, county, and State of New York, have invented certain new and useful Improvements in Car-Heaters, of which the following is a specification.

My invention aims to provide certain improvements in car-heaters and which are applicable specially though not exclusively to the heating of cars by the circulation of hot liquid, (ordinarily water.) Such systems are in general use.

According to my present invention certain improvements are provided in the stove for heating the water and in the adjacent portions of the system, whereby the efficiency and especially the safety of the apparatus are increased.

It is generally recognized that cast-iron stoves in railway-cars or even in trolley-cars are dangerous, because in case of collision they are very apt to be upset and broken, causing the burning of the car. The brittleness of a cast-iron stove is its principal point of weakness. In the present heater the danger from this cause is removed by placing the cast-iron stove in a strong sheet-metal (preferably steel) box, which even if it be smashed and crushed in the collision will yet hold in the coals and the entire cast-iron stove, even if the latter is broken in pieces. A similar casing of steel is preferably provided around the smoke-stack and adjacent parts. The steel box and casing referred to are preferably arranged to utilize the heating-surfaces of the stove and the pipe so as to obtain a maximum efficiency from the entire system. The box is also preferably arranged to facilitate access to the stove for filling it or for removing the ashes without inconvenience to the passengers. Various other advantages are referred to in detail hereinafter, and the novel features are expressed in the claims.

The accompanying drawings illustrate an embodiment of the invention.

Figure 1 is a vertical section showing the stovepipe and outgoing circulating-pipe in elevation. Fig. 2 is a section on the line 2 2 of Fig. 1, omitting the seat. Fig. 3 is a view taken at right angles to Fig. 1, partly in section and partly in elevation. Fig. 4 is a horizontal section taken on the line 4 4 of Fig. 2.

Referring to the embodiment of the invention illustrated in the drawings, A is a stove arranged, say, at the middle of one of the lon-

gitudinal sides of a car having cross-seats, as shown. The stove, however, may be arranged in any other suitable part of the car and may be used as well with cars having longitudinal seats as with those having cross-seats. It takes up very little space in the car, only the stovepipe and surrounding casing interfering with the seating-space.

B is the stovepipe extending out through a hole in the roof of the car.

The circulating system may be arranged in any suitable style. For example, it may be as described in my Patent No. 566,904, of September 1, 1896, with a tank upon the roof of the car in communication with the pipe C, the hot water from the stove going out by way of pipe D and thence through the accelerator E into the pipe F, which runs around the car according to any desired system and ends in a section G, Figs. 3 and 4, returning to the water-space in the stove. The stove A is formed with a double wall H J, Fig. 4, and the space between the two walls carries the water to be heated. The outer wall J of the stove is preferably provided with a number of openings for the discharge and return of the water. For example, there may be two holes K in the top, one of which is closed by a plug L and the other of which is used for the outgoing pipe, and there may also be three additional holes K at the upper portion of the sides of the stove for outgoing pipes, all of which are closed by plugs in the present arrangement, and there may be two holes M near the bottom of the side of the stove, one of which is closed by a plug L, while the other is connected to the ingoing pipe G. The purpose of these numerous points of connection is to permit of the use of several separate circulating systems heated from the same stove, this arrangement being sometimes preferred.

The double-walled stove is connected by a flange around its lower end with an ash-pit N, which by means of legs O is firmly connected to the base P of a sheet-metal box. This box comprises the base P and a cylindrical shell Q, constituting the sides. A top plate R for the box is mounted rigidly a short space below the top flooring of the car. The sheet-steel box comprising the base P and body or shell Q is attached to the plate R and is preferably held together by means of a number of rods or long bolts S and T. The bolts S, it will be noticed, lie just within the shell Q, so as to preserve its proper concentric position with the base P, and the bolts T

engage the outer contour of the stove, so as to hold the latter also in its proper position in the steel box. The construction thus provided is extremely simple and efficient. The parts may be quickly assembled or disassembled and are all held strongly in their proper relative positions by material which may be bent, but which will not ordinarily be broken even if the car is wrecked.

In spite of the circulation of water between the two walls of the stove there will be a certain quantity of heat radiated outward from the stove, and I propose to utilize this radiation for heating the surrounding air and to convey such heated air into the car. An air-space is also provided above the top of the stove by arranging the plate R somewhat below the floor-plate U. The steel box has a door V near its lower edge, through which are air-openings and a shutter of the style common in stove-doors. The air passes in regulated volume through the door V, circulates under and around and above the stove, and then passes up into the car, the plates R and U being also provided with perforations, as shown.

The stove is fed from inside the car through a passage W in the floor normally closed by a cover X. In order to avoid carrying ashes through the car, the stove is emptied directly outside. For this purpose the horizontally-swinging door V of the steel box is provided. This door being opened access is had to the usual means for shaking down the fire and the ash-box may be withdrawn and dumped. Thus besides saving space in the car the present arrangement is clean and permits of a very quick replenishing of the coal or other fuel.

The stovepipe is also well protected by being inclosed in a steel box or casing having double walls Y and Z. The prime purpose of the doubling of the wall is to provide a non-conducting air-space between and prevent the casing from becoming too hot to be touched. The casing at the same time incloses the outgoing hot-water pipe D. The casing has a closed upper end, and apertures are provided near the bottom through which the cold air near the floor of the car passes into the casing and is warmed by the stovepipe and the hot-water pipes D and F, and similar apertures are provided near the upper end of the casing through which the warm air passes out into the car. The casing Y Z at its back is spaced a slight distance away from the framing of the car in order to avoid overheating or charring of the latter.

The particular style of stove illustrated is specially designed for use with the other elements of the combination; but it is obvious that heaters of almost any other type might be substituted for the stove shown. The surrounding sheet-metal box and air-space are of special value where the heater is car-

ried on the outside of the car, as is substantially the case here, in preventing the exposure of the heater directly to the cold and the wind caused by the movement of the car.

Though I have described with great particularity of detail one embodiment of my invention, yet it is not to be understood that the invention is limited to the particular embodiment disclosed. Various modifications thereof in detail and in the arrangement and combination of the parts may be made by those skilled in the art without departure from the invention.

What I claim is—

1. In combination, a top plate, a box, and a heater in said box, said box comprising a bottom plate P and a shell or body portion Q the edge of which engages the face of said bottom plate, and the whole being held together by bolts S engaging said shell and bolts T engaging said heater so as to hold said parts in place against lateral movement.

2. In combination, in a car-heater, a complete sheet-metal box including a sheet-metal base-plate P and a shell or body portion Q the edge of which engages the face of said bottom plate, the whole being held together by bolts S engaging said shell and bolts T engaging said heater so as to hold said parts in place against lateral movement, and a complete cast-iron stove in said box, whereby in case of a shock sufficient to break the stove the sheet-metal box will retain the broken stove and its contents.

3. In combination, in a car-heater, a complete sheet-metal box including a sheet-metal base-plate P and a shell or body portion Q the edge of which engages the face of said bottom plate, the whole being held together by bolts S engaging said shell and bolts T engaging said heater so as to hold said parts in place against lateral movement, and a complete cast-iron stove in said box, whereby in case of a shock sufficient to break the stove the sheet-metal box will retain the broken stove and its contents, said stove having a feeding-opening accessible from the inside of the car and an ash-box accessible from the outside of the car.

4. In a car-heater, in combination, a floor-plate U, a plate R arranged below said floor-plate, a box suspended from said plate R, and a stove in said box, said box comprising a bottom plate P and a shell or body portion Q the edge of which engages the face of said bottom plate, and the whole being held together by bolts S and T connected at opposite ends to the plate R and the bottom plate P, said bolts S engaging said shell and said bolts T engaging said heater so as to hold said parts in place against lateral movement.

5. In a car-heater, in combination, a top plate, a box, and a complete cast-iron stove A in said box, said box including a sheet-metal base-plate P, and a cylindrical sheet-

metal plate Q forming the sides, the whole being held together by bolts S and T attached to said top plate and to said base-plate, said bolts S extending alongside of and engaging said cylindrical plate Q, and said bolts T extending alongside of and engaging said stove A, whereby the sides and the stove are held in place against lateral movement.

6. In a car-heater, in combination, a top plate R and a floor-plate U having an air-space between them, a box, and a complete cast-iron stove A in said box, said box comprising a sheet-metal base-plate P and a cylindrical sheet-metal plate Q forming the sides, the whole being held together by bolts S and T passing through and attached to said plates

R and P, said bolts S being adjacent to and engaging said cylindrical plate Q, and said bolts T being adjacent to and engaging said stove, so as to hold said parts in place against lateral movement, and an air-space being provided around said stove between the stove and the box, and suitable apertures being provided for the passage of air through said space and through the floor-plate U.

In witness whereof I have hereunto signed my name in the presence of two subscribing witnesses.

EDWARD E. GOLD.
